UNITED STATES PATENT OFFICE.

EBENEZER HILL, OF SOUTH NORWALK, CONNECTICUT, ASSIGNOR TO THE HILL COMPRESSOR & PUMP COMPANY, OF NEW YORK, N. Y., A CORPORATION OF DELAWARE.

PACKING MEANS FOR ROTARY PUMPS.

Application filed May 1, 1923. Serial No. 635,852.

To all whom it may concern:

Be it known that I, EBENEZER HILL, a citizen of the United States, residing at South Norwalk, in the county of Fairfield and State of Connecticut, have invented a new and useful Improvement in Packing Means for Rotary Pumps, of which the following is a specification.

This invention relates to a rotary pump, compressor, or similar apparatus hereinafter termed "pump", for compressing or exhausting fluids, and more particularly fluids having dangerous or destructive properties.

The object of the invention is to so construct the apparatus that the pumping can be continuously carried on with safety and without material injury to the wearing parts.

To this end the pump has a pumping member rotating in a closed pumping chamber within the casing and a suitable bearing for the pumping member located exteriorly to the pumping chamber either within the casing or outside of it, as the design of the apparatus may require. For preventing leakage to and from the pumping chamber, the rotor which may be either the pumping member, or its hub, or the driving shaft, is provided with an automatically expandable packing means interposed between the pumping chamber and the bearing, said means consisting of a rotatable packing member, a co-operating non-rotatable packing member, and a resilient element arranged to form a gas tight connection between one of the packing members and the casing and confine any leakage to or from the pumping chamber to a leakage cavity. The resilient element is so constructed and arranged that the pressure of any leakage is utilized to force the packing members into tight sealing engagement, which sealing engagement is consequently directly proportional to the pressure on opposite sides of the resilient element and this maintains a uniform sealing engagement around the entire circumference of the contacting surfaces of the packing members.

Lubricant can be introduced into the leakage cavity for the purpose of effecting a liquid seal and preventing the compressed fluid from coming into contact with the engaging surfaces of the packing members, if desired.

In the drawings Fig. 1 shows a longitudi-

nal section of a pump having the main bearing for the rotor contained within the casing and the packing interposed according to this invention between the bearing and the pumping chamber. Fig. 2 is a similar section of a pump with the main bearing mounted in a frame exterior to the casing.

The pump may be of any usual or approved type, comprising one or more rotary pumping members and the main bearing for the rotor or rotors may be located within the casing or may be located exterior thereto, but in every case, the main bearing is exterior to the pressure chamber, so that there will be no possibility of the compressed fluid coming into contact with the bearing or leaking therethrough when the apparatus is in operation. This is particularly essential in pumps employed for the compression of explosive, inflammable, or corrosive gases, such as oxygen, hydrogen, acetylene, ammonia, chlorine, etc., as otherwise damage is liable to occur. Further, this construction permits of a lubricant being used in the pressure chamber which is not harmful to, and which has no reaction with, the gas being compressed, and it also permits of a lubricant being used in the bearing which could not otherwise be used with safety.

In the preferred construction illustrated the pump casing 5 is cylindrical and has a head 6 secured to it in such manner that it may be removed to give access to the interior of the casing. The head has a hub 8 in which is mounted the journal 9 of the arbor 10 for the inner pumping member 11. Surrounding and co-acting with the inner pumping member 11 is the outer pumping member 12, the perimeter of which fits snugly but rotatably in the casing 5.

The inner face of the head 6 is in contact with the adjacent faces of the pumping members 11 and 12, and in conjunction with those members and the casing 5 forms a pumping chamber in which the compression or exhaustion of the gases is effected, the outer pumping member 12 for this purpose having a closed side 13. As shown in Fig. 1, a hub 14 extends axially from the side 13 of the outer pumping member in a direction opposite from the head 6 and entered in the bore of the hub is the actuating shaft 15 which rotates the outer member 12.

Within the casing 5 are bearings 16 and mounted in these bearings is the hub 14.

The bearings as shown in Fig. 1 are exterior to the pumping chamber and separated from it by a leakage cavity in which the packing hereinafter described is contained.

- 5 To prevent the inward displacement of the bearing 16 the inner wall of the casing 5 is formed with an annular shoulder 17 opposed to the adjacent face of the bearing, and between this shoulder and the bearing 10 is a ring 30. Encircling the hub 14 on the outer side of the bearing 16 is the stuffing box 18 for the lubricant retaining packing ring 19. This stuffing box 18, which is secured in place by bolts 20, engages the bearing 15 and forces it inward. On the hub 14, preferably in juxtaposition to the back of the outer pumping member is a fillet 21, which may be either an integral part of the rotatory part or may be a separately made 20 ring shrunk gas tight on the hub. This fillet which is shown with a curved face acts as the rotatable packing member employed to prevent the escape of fluid to or from the pumping chamber. Encircling the fillet is 25 a ring 22 having a contacting surface correspondingly shaped to that of the fillet and establishing a sealing engagement therewith. This ring acts as the non-rotatable packing member.
- 30 One extremity of the gas tight resilient packing element, shown in the form of a bellows 23, is welded, brazed, or otherwise tightly connected or anchored to the packing member 22 and the other end of this expandable member is brazed, welded or otherwise connected to the ring 30 that is anchored 35 between the shoulder 17 on the casing and the bearing 16. The pressure exerted on the stuffing box 18 and bearing 16 by the bolts 40 20 causes the bearing 16 to clamp the ring 30 against the shoulder 17 and establish a gas tight joint between the packing and the casing. This construction provides a leakage cavity 24 at the back of the outer pumping member 12 and shuts off all communication 45 between the leakage cavity and the bearing so that any fluid escaping from the pumping chamber through the working clearance between the pumping members and 50 the casing will be prevented from reaching the bearing 16 and from escaping from the apparatus at this side of the casing.
- The packing element 23 consists in the case illustrated of a corrugated resilient 55 metallic tube and should any fluid leak from the pumping chamber to the leakage cavity its pressure would tend to spread the convolutions of this member and extend it. Such an expansion of the packing element 60 23 will force the non-rotatable packing ring 22 toward the rotatable fillet 21 and increase the force of the sealing engagement of these packing members.

When the apparatus is employed for 65 vacuum work it is necessary to prevent

leakage from the atmosphere to the pumping chamber. For such uses the apparatus is provided with the described packing but instead of the cavity receiving leakage from the pumping chamber the atmospheric pressure being greater on the outside of the resilient element causes the expansion of that member, and the forcing of the rotatable and non-rotatable packing members together as previously described.

In Fig. 1 the rotor is assumed to be the rotatable pumping member and its hub in which the actuating shaft is entered. In the form shown in Fig. 2 the pumping member is constructed without a hub, and the actuating shaft 25 is secured directly to it. In this construction the rotary packing member 21 may be either integral with or applied to the shaft and it may be either in juxtaposition to the pumping member or spaced therefrom. The stationary packing member 22 and the resilient packing element 23 in this form are as previously described, but the outer extremity of the expandable packing element 23 is fastened to the ring 30 which is clamped between the shoulder 17 and the stuffing box 18. In the second form illustrated the shaft bearing 31 is independent of the pump casing.

The term "rotor" as used throughout the specification is to be understood to include within its meaning the rotatable pumping member or its hub or the driving shaft, and it is to be understood that the packing can be assembled with any one or all of these parts.

If the pump provided with a packing similar to that described is being used for pumping inflammable, explosive or otherwise dangerous or obnoxious gas, it is impossible for such gas, if there should be any leakage around the pumping elements, to escape further than the leakage cavity where no damage would result. This is particularly so if the leakage cavity is filled with lubricating or packing fluid which substance may be such as will not dilute or injuriously affect the gas being pumped. The main bearings of the pumping element are protected by this form of packing against the deleterious action of corrosive gas being pumped and furthermore the bearings may be lubricated with suitable material that would form an explosive mixture or deleteriously affect the gas being pumped for the bearing lubricant is effectively shut off from the pumping chamber by the packing which is kept tight regardless of wear according to the degree of difference in pressure on the inside and outside of the packing.

The invention claimed is:—

1. A rotary pump comprising a casing having a pumping chamber and a leakage cavity communicating with the pumping chamber, a rotor rotatably fitting said

chamber and closing one end of the leakage cavity, a bearing for the rotor exterior to the pumping chamber and leakage cavity, and an expansible packing interposed and forming a wall between the leakage cavity and the bearing whereby fluid pressure leaking from the pumping chamber to the leakage cavity is prevented from escaping through the bearing and is caused to exert pressure against the back of the rotor.

2. A rotary pump comprising a casing having a pumping chamber and a leakage cavity communicating with the pumping chamber, a rotor rotatably fitting said chamber and closing one end of the leakage cavity, a bearing for the rotor exterior to the pumping chamber and leakage cavity, and an expansible packing interposed and forming a wall between the leakage cavity and the bearing whereby fluid pressure leaking from the pumping chamber to the leakage cavity is prevented from escaping through the bearing and is caused to force the rotor forward to reduce leakage from the pumping chamber to the leakage cavity.

3. A rotary pump comprising a casing having a pumping chamber and a leakage cavity communicating with the pumping chamber, a rotor rotatably fitting said chamber and closing one end of the leakage cavity, a bearing for the rotor exterior to the pumping chamber and leakage cavity, and an expansible packing having rotatable and stationary contacting members, interposed and forming a wall between the leakage cavity and the bearing whereby fluid pressure leaking from the pumping chamber to the leakage cavity forces said contacting members into sealing engagement and presses against the back of the rotor with a force dependent upon the difference in pressure on opposite sides of said packing.

4. A rotary pump comprising a casing having a pumping chamber and a leakage cavity communicating with the pumping chamber, a rotor rotatably fitting said chamber and closing one end of the leakage cavity, a bearing for the rotor exterior to the pumping chamber and leakage cavity, and a packing consisting of a fillet on the rotor, a packing ring engaged with the fillet, and a gas tight expansible sleeve, connected with the packing ring and casing, said packing interposed and forming a wall between the leakage cavity and the bearing whereby fluid

pressure leaking from the pumping chamber to the leakage cavity is prevented from escaping through the bearing and is caused to exert pressure against the back of the rotor.

5. A rotary pump comprising a casing having a pumping chamber and a cavity adapted to receive lubricating material communicating with the pumping chamber, a rotor rotatably fitting said chamber and closing one end of said cavity, and an expansible packing interposed and forming one wall of the leakage chamber whereby fluid pressure leaking from the pumping chamber to the leakage chamber is caused to exert pressure against the back of the rotor and to force lubricant from said cavity to effect a seal between the casing and the rotor.

6. A rotary pump comprising a casing having a pumping chamber and a leakage cavity communicating with the pumping chamber, a rotor rotatably fitting said chamber and forming one wall of said cavity, and an expansible packing forming another wall of said cavity, whereby fluid pressure leaking from the pumping chamber to the leakage cavity is confined and caused to exert pressure against the back of the rotor.

7. A rotary pump comprising a casing having a pumping chamber and a leakage cavity communicating with the pumping chamber, a rotor rotatably fitting said chamber and closing one end of the leakage cavity, and an expansible packing comprising a fillet rotatable with the rotor, a stationary ring fitted to said fillet, and a corrugated sleeve fitted gas tight to said ring and to the casing, said packing forming a wall of the leakage cavity whereby fluid pressure leaking from the pumping chamber to the leakage cavity is confined and caused to exert pressure against the back of the rotor.

8. A rotary pump comprising a casing having a pumping chamber and a leakage cavity communicating with the pumping chamber, a rotor rotatably fitting said chamber and closing one end of the leakage cavity, and an expansible packing sleeve forming a wall of the leakage cavity, said packing sealing the cavity back of the rotor with a pressure dependent on the difference of pressure on opposite sides of the packing.

EBENEZER HILL.
